UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

ATTACHMENT FOR SEWING MACHINES.

1,359,877.

Specification of Letters Patent. Patented Nov. 23, 1920.

Application filed December 2, 1918. Serial No. 264,898.

To all whom it may concern:

Be it known that I, ALBERT H. DE VOE, a citizen of the United States, residing at Westfield, in the county of Union and State 5 of New Jersey, have invented certain new and useful Improvements in Attachments for Sewing-Machines, of which the following is a specification, reference being had therein to the accompanying drawings.

10 This invention relates to attachments for sewing machines and more particularly to the type of attachments known as hemmers.

The introduction and removal of work 15 from hemmers requires dexterity of an order not possessed by all operatives and it has long been found desirable to construct such devices in sections one of which may be conveniently displaced, shifted or otherwise 20 moved to facilitate the introduction of work. The present invention is applied to such type of hemmers and aims to provide new and improved mechanism for shifting one 25 section of the hemmer in a prescribed path not likely during the displacement to disarrange the previously formed hem, in the case of circular work, and in all cases requiring a minimum of time and energy to operate.

30 In its preferred form the construction comprises a hemmer divided longitudinally into base and roof sections the former of which is integral with a base-plate grooved transversely of the line of feed to receive 35 an extension from the latter (*i.e.* roof) section which is thereby confined to move in a vertical plane transverse the line of feed. Lift and shift levers are arranged to simultaneously reciprocate and elevate the roof 40 section and these levers are both actuated by a treadle operable lever in one case through a projection thereon and in the other case through a toggle linkage that shifts the roof section first away from the base section 45 and then back toward it, the lift lever being timed to elevate the roof section when liability of disarrangement of the hem by the base section is excluded. In this way the roof section may be moved outwardly, upwardly 50 and backwardly from a position in hemming relation with the base-section to a position to the opposite side of and above the base-section.

The invention is illustrated in the accom-

panying drawings in which Figure 1 is a 55 plan view of the attachment applied to a sewing machine. Fig. 2 is a side elevation of the same, part of the apron depending from the cloth-plate being broken away to expose the construction, and Fig. 3 is a detail in side elevation of the roof section of the hemmer.

The device may be used with any suitable sewing machine, as illustrated, being applied to a single needle type of the Singer 65 No. 62 class in which the needle is adapted to pass through a needle-hole 1 in a throat-plate 2 provided with slots 3 for a feed-dog 4. A cover-slide 5 extending alongside of the throat-plate is removably fitted in suitable guideways 6 in the cloth-plate 7, leaf-springs 8 being attached to the cover-slide to yieldingly retain the same in place against displacement during the operation of the machine when vibration is likely. 75

Mounted on the cover-slide is a base-plate 9 which is provided with a slot 10 receiving clamp-screws 11 for adjustably securing the base-plate to the cover-slide. Upstanding parallel ribs 12 on the base-plate define a 80 groove 13 disposed transversely of the line of seam-formation. To one side of the base-plate 9 and in advance of the needle-hole 1 is soldered or otherwise suitably secured a base-section 14 of the hemmer which has a 85 concaved upstanding wall 15. This wall 15 terminates in a substantially straight edge 16 into contact with which a similar straight edge of the convolute roof section 17 is adapted to be brought to complete the continuity of the hemmer. The sectional hemmer thus constituted is similar in operation to those on the market and needs no further description. 90

The roof section 17 is soldered or otherwise suitably secured to a bar or slide 18 of the irregular shape shown best in Fig. 3 and the slide 18 is received within the groove or channel 13 defined by the upstanding ribs 12. 95

The slide 18 is provided at its right hand side, as shown in Fig. 3, with a pin 19 which is received within the slot 20 provided in the front upstanding rib 12. By this pin and slot connection the roof section 17 of 100 the hemmer is permitted to be shifted parallel with the cloth-plate and to be swung in a direction transverse the cloth-plate. To 105

confine the roof section in coöperative hemming relation with the base section a coiled spring 21 reacting against the abutment 22 is arranged to urge the roof section toward 5 the right as viewed in Fig. 2. A pin 23, in the rear upstanding rib 12 and adapted to enter the open-ended slot 24 in the lower part of the slide 18, also assists in confining the roof section of the hemmer when it is about 10 to move into or away from coöperative hemming relation with the base-section.

The construction thus far described is a sectional hemmer whose roof portion may be swung outwardly, upwardly and backwardly, means being provided to confine the roof section to move in a vertical plane transverse the line of feed and means also being provided to maintain the sections of the hemmer in coöperative hemming relation. 15

The roof section is arranged to be moved or shifted from its normal working relation with the base section in a curved path by the combined action of two levers, one, a 25 lift lever 25, pivoted at 26 to the front upstanding rib 12 and having a depending end 27 by which it may be lifted to engage a pin 28 extending forwardly from the slide 18 carrying the roof section of the hemmer, 30 and the other, a vertically arranged shift lever 29 pivoted at 30 below the cloth-plate of the machine with its upper end 31 projecting through a slot 31' in the cloth-plate above which it is connected to the roof section 35 of the hemmer by a link 32 carrying a pin 33 adapted to seat in an upwardly open slot 34 in an enlarged portion 35 of the bar or slide 18. A spring 36 coiled about the pivotal connection between the link 32 and the shift lever 29 has its opposite free 40 ends caught about the link and shift lever and tends to hold the pin 33 in the slot 34 of the slide 18. This last-mentioned construction constitutes a detachable connection 45 that permits removal of the hemmer *per se* when it is desired to clear the cloth-plate for general stitching.

The lift lever 25 and the shift lever 29 are both actuated from a manually operable 50 lever 37 which is fulcrumed on the stud-pin 38 and is normally held in an elevated position by a coiled spring 39 as will be obvious from an inspection of the drawings. Fixedly secured to the lever 37 is a finger or projection 40 which is adapted to strike the downwardly extending end 27 of the lift lever. It will be noticed that the finger or projection 40 lies almost directly above the axis 55 of the stud 38 and that consequently force is advantageously applied to actuate the lift lever 25. The manually operable lever 37 at its free end is connected to an intermediate portion of the shift lever 29 by a toggle link 41. Connected to the lever 37 60 through a perforation in an ear 42 is a rod

or wire 43 that may be operated by a treadle or knee shift (not shown) in a manner well understood.

It will be noticed that the link 41 has a toggle action upon the shift lever 29. This 70 will be clear upon inspection of Fig. 2 of the drawings by comparison of the positions assumed by the lever 37 and link 41 with relation to the shift lever 29 indicated by dotted and solid lines, the latter showing 75 the linkage in the position occupied by its parts when the roof section of the hemmer is in coöperative hemming relation with the base section and the former when in non-coöperative relation. By a single down stroke 80 of the manually operable lever 37 the shift lever is first shifted to the left (viewed as in Fig. 2), then its direction of motion is reversed and it is shifted to the right. While the roof section is being shifted through the 85 shift lever 29 and toggle 41, the finger or projection 40 moves into contact with the down-turned end or cam portion 27 of the lift lever 25 and elevates the roof section. The result is that the roof section is moved 90 in a curved path. Preferably the roof section is not raised or elevated by the lift lever 25 until the arbor portion 17' has been moved to the left beyond the edge or edge-fold of the hem, the delay being insured by 95 the pin-and-slot connection 23-24. By delaying the timing of the lift lever's action as mentioned liability of disarrangement of the condition of the hem in the completion of circular work is avoided. When the 100 lever 37 is released to the action of its own spring the operations are of course reversed.

While the invention has been illustrated and described as applied to a sectional hemmer it will be obvious that it is capable of 105 application to a binder or other folder and in its broader aspects includes the application of the mechanism to any sort of an attachment wherein is employed a part or section that it is desirable to shift at one 110 time or another.

Having thus set forth the nature of the invention, what I claim herein is—

1. A folder for sewing machines having base and roof sections separable to facilitate the introduction and removal of work, and means for shifting said roof section outwardly, upwardly and laterally from a normal working position in which the folder is capable of folding material to an abnormal position in which the folder is not capable of folding material. 115

2. A sectional folder for sewing machines having at least two relatively separable sections, means for maintaining said sections together in coöperative relation and means for shifting one of said sections from a working position at one side to an inoperative position at the other side of the rest 125 of the folder. 130

3. A hemmer for sewing machines divided longitudinally into base and roof sections, said roof section being shiftable to opposite sides of the base section, and treadle operable means for shifting the roof section laterally, and means for lifting the roof section whereby the roof section may be moved laterally and upwardly with relation to the base section.
4. In a sewing machine having a work-support and presser-foot, a hemmer divided laterally into base and roof sections and supported by the work-support independently of the presser-foot, means for maintaining the sections in coöperative hemming relation, and means arranged beneath the work-support for shifting one of the hammer sections in directions substantially parallel with and perpendicular to the work-support whereby one of the hemmer sections may be shifted without disarranging the material being hemmed.
5. A folder for sewing machines having separable sections, mechanism for shifting one of said sections in a curved path including lifting and shifting devices and a common actuator for simultaneously operating said devices.
6. A folder for sewing machines having separable sections in combination with means for shifting one section relative to another including a lever and a toggle mechanism for operating the same adapted to move it in a plurality of different directions during operation of the toggle mechanism in a single direction.
7. A hemmer for sewing machines having a base-plate provided with a groove, a base section fixed to said base-plate, a roof section, a slide supporting the roof section and movably arranged within said groove, means connecting said slide and base-plate permitting movement of the roof section in a curved path, a lift lever for elevating and a shift lever for reciprocating the roof section, a manually operable lever, and devices connected to said manually operable lever for actuating the lift and shift levers to move the roof section to and from normal hemming relation with the base section.
8. A folder for sewing machines having complementary portions, means for relatively moving said portions including lift and shift levers for elevation and reciprocation respectively of one of the complementary portions, and a manually operable lever for actuating the first mentioned levers.
9. A hemmer for sewing machines divided into sections for separation to facilitate introduction and removal of the work, a spring for yieldingly holding the sections in normal coöperative hemming relation, mechanism for shifting one of the sections to and from its normal hemming position including a manually operable lever, a lift lever, means connected to the manually operable lever for actuating the lift lever a shift lever, means operatively connecting the shift lever and one section of the hemmer, and means for reciprocating the shift lever by movement of the manually operable lever in one direction.
10. A hemmer for sewing machines divided into sections for separation, means for maintaining said sections in coöperative hemming relation, shift and lift levers for moving one of said sections to and out of the way position facilitating the introduction of work, a manually operable lever having a projection for operating the lift lever and also having a link connection with the shift lever, and means coöperating with the shift and lift levers to transmit their motions compounded to said one movable section of the hemmer.
11. A hemmer for sewing machines divided into sections for separation, means for maintaining said sections in coöperative hemming relation, shift and lift levers for moving one of said sections to a position facilitating the introduction and removal of work, a treadle operable lever having an element fixed thereto for operating the lift lever, a link connecting the shift lever with the treadle lever so as to have a toggle action, and a spring for normally holding the treadle operable lever in a position in which the sections of the hemmer are in coöperative hemming relation.
12. A hemmer for sewing machines divided into sections for separation, a slide with an overhanging free end by which one of the sections is carried, means confining movement of said slide to a predetermined plane, a compound pivotal and sliding connection between the slide and the means confining it, means for shifting the slide, means for swinging the slide, and means for confining the slide to move in a substantially straight line during the last part of its movement when the sections of the hemmer are brought into coöperative working relation capable of forming material into a hem.

In testimony whereof, I have signed my name to this specification.

ALBERT H. DE VOE.
